DREDGING APPARATUS

Williard Rea Ewing, Libertyville, Ill., assignor to
McWilliams Dredging Company, Chicago, Ill.,
a corporation of Illinois

Application August 18, 1934, Serial No. 740,475

8 Claims. (Cl. 37—67)

This invention relates to hydraulic dredging apparatus and more particularly to means for anchoring the same.

In accordance with known practices, on floating hydraulic dredges, two anchors are customarily employed, the anchors being spaced laterally from the dredge boat at points approximately opposite the front end, during operation. Prior to the use of the present invention, these anchors were lifted and moved, from time to time, as the dredging process required, by means of barges or boats separate from the main dredge boat. These barges were provided with hoisting apparatus to raise and lower the anchors but inasmuch as the anchors for large dredges were often quite heavy, several men were required to hoist an anchor, move it to a new position and drop it. This manner of moving the anchor required considerable time, during which dredging operations had to cease and the anchors were often not dropped the same distance in advance of the dredge boat so that care had to be exercised in order to avoid uneven dredging or cutting. Also, where the dredging operation was in a swamp, navigation of the auxiliary anchor barges was difficult or impossible.

It is an object of the present invention to provide means to remedy these conditions by providing an arrangement for anchoring a dredge boat which is capable of operation in all kinds of places.

It is a further object to provide anchor moving and locating means which are capable of speedily and accurately moving anchoring devices and which can be operated from the main dredge boat without the use of auxiliary barges or the like.

Other objects and advantages reside in certain novel features of the arrangement and construction as will be apparent from the following description, taken in connection with the accompanying drawings, in which:

Figure 1 is a fragmentary plan view of a dredge boat showing portions of the invention attached thereto;

Figure 2 is a view in side elevation of a portion of the apparatus of Figure 1 and showing one of the anchors in position;

Figure 3 is a diagrammatic showing, in plan view, illustrating the operation of the invention;

Figure 4 is a fragmentary plan view illustrating the construction of a detail of the supporting structure; and

Figure 5 is a fragmentary plan view of the front end of a dredge boat constructed in accordance with the invention and showing means

adapted to support parts of the A frame, the ladder and an anchor boom thereof.

Referring to the drawings in detail and particularly to Figures 1 and 2 it will be seen that a portion of a hull of a dredge boat is indicated by the reference character 11. A suitable enclosure 12 may be provided for housing the engine, pump, hoisting drums etc. in accordance with known practices.

Near the front end of the dredge boat, a supporting structure or gallows frame 13 is provided, which, by means of cables or chains supports the upper end of an A-frame 14 and through it, the front end of the ladder 15, to which the cutter 16 and suction line 17 of the hydraulic dredge are attached. The ladder 15, together with the cutter 16 and suction line 17 are supported on the A-frame 14 by means of cable 43 (connected to a suitable drum on the deck, not shown) and the pulley blocks 44 and chains 45. The A-frame 14 and the ladder 15 are pivotally mounted on the front end of the dredge boat at two points spaced slightly inwardly from the sides of the hull. As indicated in Figure 5, a single casting 18 may be employed for this purpose. In the arrangement shown, the A-frame 14 is pivoted to the members 18 slightly above the top of the deck while the ladder 15 is pivoted to these members at the front of the hull 11 and some distance below the deck.

Two cables 19 (see Fig. 2) of fixed length normally support the A-frame 14 on the gallows frame 13. In accordance with the present invention the stress on these cables may be wholly or partially relieved by the auxiliary supporting structure indicated by the reference characters 20, 21, 22, 23, although the primary purpose in this auxiliary assembly is to provide means for supporting the two anchor booms shown at 24. The anchor booms constitute important parts of the invention and will be explained hereinafter.

In order to support the anchor booms so as to cause them to operate properly, it is necessary to provide fixed pivot points for them. For this purpose boom feet 25 (see Fig. 5) are secured to the hull just outside the location of the pivotal supports 18 for the A-frame and ladder. This readily solves the problem of supporting the lower ends of the anchor booms. To support the upper ends of the anchor booms is not so simple. It would naturally be supposed that cables could easily be rigged from the anchor booms to suitable points on the supporting cables 19 but it has been found by experience that this arrangement is not at all satisfactory. The A-frame 55

must be held in fixed position by the cables 19 and this cannot be accomplished if booms are hung on them.

In accordance with the present invention, a floating spar or strut member 22 is supported from the gallows frame 13 and A-frame 14 by a set of cables 20 and 23, together with the bracing cables 21. The location of the strut 22 is important. As shown in Figure 1, it is slightly in front of the front edge of the boat so that the ends of the strut occupy positions slightly in front of, and slightly outside of the feet 25 for the anchor booms.

The upper ends of the anchor booms 24 are suspended from the outer ends of the strut 22 by means of cables 26. Auxiliary cables 27 may also extend from the ends of the strut 22 to some intermediate points of the anchor booms 24.

By employing the strut 22 and the cables 20, 21 and 23 arranged as shown, there is very little tendency to raise the A-frame due to the weight of the booms 24.

This will be apparent when it is noted that because of the length of the strut 22, the outer ends of the strut, at the points where the cables 20 and 23 are attached thereto, are outside of the shortest line from the gallows frame 13 to the A-frame 14. Thus, with the anchor booms 24 not attached to the strut 22, this member is under compression due to the weight of the A-frame. When the anchor booms 24 are suspended on the ends of the strut 22, the resultant forces on the strut 22 may change from compression to tension, but the strut and the A-frame will not move. The horizontal component of the force resulting from the weight of the booms will be taken up by the strut 22 and by the cables 29 so long as the booms are in advance of the front end of the dredge boat. There will be very little if any vertical stress thrown upon the cables 20 and 23 by the booms. In fact, it is possible to make the cables 26 and 27 of such a length that the ends of the booms are at the same height as the strut 22 in which case there would be no vertical component of force on the cables 20 and 23. Under these circumstances, the booms could not be used to best advantage, however, because their ends would not be spaced as far from the dredge boat as in the arrangement indicated. Two anchors (one of which is shown at 28 in Figure 2) are employed to hold the front end of the dredge boat in position. During digging operations, these anchors are set at points spaced laterally from the front end of the boat, and are connected to the boat through cables 29 which run over sheaves 30 on the ladder 15, sheaves 31 on the A-frame and from there to suitable drums 32 on the main deck which may be operated by an electric motor 33 or the like. By hauling in one cable 29 and letting out the other, the dredge boat may be swung about either of the rear spuds 34 (see Fig. 3).

In order to move the anchors 28 from one location to another, cables 35 are connected there-to and pass upwardly through sheaves 36 on the anchor booms 24, thence to sheaves 37 on the upper part of the A-frame 14, downwardly along the A-frame 14 to sheaves 38, located as low on the A-frame as is convenient and from there to drums 39 on the deck. The drums 39 may be actuated by suitable gearing and clutches from a shaft 40 driven by an electric motor 41.

Because of the fact that the sheave 38 is located rather low on the A-frame 14, the tendency 75 to raise the A-frame by pulling on the cables 35

is slight, even though the load on these cables is high and the booms 24 are swung out laterally to considerable extent.

In the showing of Figures 1 and 2, the booms 24 are shown broken away. They may be of considerable length and during normal operating conditions would extend out laterally at nearly right angles to the longitudinal center line of the boat (see Fig. 3). Cables 42 of fixed length are used to limit forward movement of the booms 10 24. In Figures 1 and 2 these are also shown as broken away.

The operation of the anchoring and anchor moving means is as follows:

Assuming that the anchors 28 are in position 15 at points beneath the ends of the booms 24, digging operations may be carried on, the entire dredge boat being swung about one or the other of the spuds 34 by pulling on one or the other of the cables 29 to move the cutter and suction line 20 back and forth across the channel. As the dredging proceeds the boat is moved forward, gradually to the dotted line position indicated, although the anchors remain in the same position.

In moving the boat forward, one spud, and then the other, is raised as the dredge is swung back and forth by the cables 29 so that the dredge is "walked" forward. Thus in Figure 3, the spud 34 shown at the top of the figure may be raised. 30 The boat then pivots about the spud shown on the lower side of the figure, and as the boat is swung toward the right (as viewed from the left of the drawing) the left spud is advanced. If the left spud is now set, the right one raised, and the dredge swung to the left, the boat is advanced correspondingly. This provides means for moving the dredge forward accurately as the digging proceeds. To secure best operation, it is important to also move the anchors forward accurately distances, although the anchors need not be moved every time the boat swings back and forth.

If now it is desired to move the anchor 28 shown in Figure 3 forward, the dredge is swung to the right, (as viewed from the left of the figure) so that the boom 24 shown is approximately over the anchor. The cable 42 will then be loose because of the position of the boom. By operating the right hand drum 39, the right hand cable 35 will be tightened and the anchor lifted. Due 50 to the fact that the end of the strut 22 is in advance of and outside of the boom foot 25, the boom 24 will tend to swing forward by gravity. It is not necessary to exert much force on the cable 35, therefore, to swing the anchor forward. The forward movement of the boom 24 being limited by the cable 42, the anchor may be accurately positioned before being dropped.

After the anchor 28 has been positioned, the boat may be swung to the left and the anchor 60 not shown in Figure 3 may be advanced in the same way.

It is desirable to maintain a slight tension on the cables 35 at all times in order that the booms 65 may be held in operative position and in order that the operator may be apprised of the position of the anchors by noting the position of the booms. The clutches used for operating the drums 39 may be so constructed as to "drag" a 70 little at all times so as to maintain the requisite tension on the cables 35.

While only one embodiment of the invention has been shown and described herein, it is obvious that many changes may be made without de- 75

parting from the spirit of the invention or the scope of the annexed claims.

I claim:

1. In combination, a hydraulic dredge boat having a gallows frame, an A-frame and a ladder mounted on the front end of a hull, two anchors for holding the front end of the hull in position for dredging, cables connected to said anchors and passing over sheaves on said ladder, operating drums mounted on the hull and connected to said cables for swinging the front end of said boat back and forth between said anchors, two anchor booms having their lower ends pivotally mounted on said hull, means for supporting the upper ends of said booms, comprising a strut member, cables for supporting said strut member laterally of the boat between the said gallows frame and said A-frame at a point slightly in advance of the lower ends of said booms, cables extending from said strut member to the upper ends of said booms and power actuated cable means connecting said anchors to said booms for supporting the anchors on said booms and for moving said booms.
2. In combination, a dredge boat having a gallows frame and an A-frame, two anchors for holding the boat in position for dredging and an arrangement mounted on the boat for moving said anchors, said arrangement comprising two anchor booms pivotally mounted on said boat, a strut member, means for supporting said strut member from said gallows frame and said A-frame, means for supporting said booms from said strut member and power actuated means for supporting said anchors on said booms and for swinging said booms.
3. In combination a dredge boat having a gallows frame and an A-frame on the front end thereof and two spuds on the rear end thereof, two anchors for holding the front end of the boat in position for dredging, cables connected to said anchors for swinging the dredge boat about one or the other of said spuds, and an arrangement mounted on said boat for moving said anchors, said arrangement consisting of two anchor booms having their lower ends pivotally mounted on the front end of said boat near the sides thereof, means for supporting the upper ends of said booms at points between said gallows frame and said A-frame and power actuated means for supporting the anchors on said booms and for moving said booms.
4. In combination, a dredge boat having a gallows frame and an A-frame on the front end thereof and two spuds on the rear end thereof, two anchors for holding the front end of the boat in position for dredging, cables connected to said anchors for swinging the dredge boat about one or the other of said spuds, and an arrangement mounted on said boat for moving said anchors, said arrangement consisting of two anchor booms having their lower ends pivotally mounted on the front end of said boat near the sides thereof, a strut member, means for supporting said strut member from said gallows frame and said A-frame in such position that it extends transversely of the boat with its ends above, slightly in advance, and slightly outside of the lower ends of said booms, means for supporting the upper ends of said booms from

the said strut member and power actuated means for supporting said anchors on said booms and for swinging said booms.

5. In combination, a dredge boat having a gallows frame and an A-frame on the front end thereof and two spuds on the rear end thereof, two anchors for holding the front end of the boat in position for dredging, cables connected to said anchors for swinging the dredge boat about one or the other of said spuds, and an arrangement mounted on said boat for moving said anchors, said arrangement consisting of two anchor booms having their lower ends pivotally mounted on the front end of said boat near the sides thereof, a strut member, means for supporting said strut member from said gallows frame and said A-frame in such position that it extends transversely of the boat with its ends above, slightly in advance, and slightly outside of the lower ends of said booms, means for supporting the upper ends of said booms from the said strut member and power actuated means for supporting said anchors on said booms and for swinging said booms, said last mentioned means including cables extending from drums on said boat to points on said A-frame, from there to the ends of said booms and from there to said anchors, the arrangement being such that the anchors are swung by gravity when supported on said booms.

6. In a dredge boat having a gallows frame and an A frame on the front end thereof, an anchor for holding said boat in position for dredging and an arrangement for moving said anchor, said arrangement including a boom having its lower end pivoted to the deck of said boat, means for supporting the upper end of said boom to enable said upper end to swing about an upper pivot point in advance of said gallows frame and in the rear of the upper end of said A-frame and means for supporting said anchor on said boom.

7. In a dredge boat having a gallows frame and an A frame on the front end thereof, an anchor for holding said boat in position for dredging and an arrangement for moving said anchor, said arrangement including a boom having its lower end pivoted to the deck of said boat, means for supporting the upper end of said boom to enable said upper end to swing about an upper pivot point in advance of said gallows frame and in the rear of the upper end of said A-frame, means for supporting said anchor on said boom and means for limiting forward movement of said boom.

8. In a dredge boat having a gallows frame and an A frame on the front end thereof, an anchor for holding said boat in position for dredging and an arrangement for moving said anchor, said arrangement including a boom having its lower end pivoted to the deck of said boat, means for supporting the upper end of said boom to enable said upper end to swing about an upper pivot point in advance of said gallows frame and in the rear of the upper end of said A-frame, means for supporting said anchor on said boom and means for limiting forward movement of said boom, the arrangement being such that when the anchor is supported on said boom, the boom tends to swing forwardly by gravity action.
